FEEDING MECHANISM FOR SEAL-STAMPING MACHINES

Franz Leo Stoffel, Arbon, Switzerland, assignor to
Hans F. Stoffel, New York, N. Y.Application January 27, 1939, Serial No. 253,237
In Switzerland January 31, 1938

1 Claim. (Cl. 193—10)

My invention relates to improvements in feeding mechanisms for seal-stamping machines located between the hopper mechanism and the sealing mechanism; and the objects of my improvement are, first, to provide at the head of the blank-chute a pickup-and-kickout device; second, to afford facilities for the proper guiding of the selected blanks; and, third, to provide means at the foot of the feeding mechanism for positively and continuously feeding the blanks toward and under the stamp.

The subject of the invention is illustrated by way of example in the accompanying drawings in which:

Fig. 1 is a front view of an automatic machine 15 in perspective.

Fig. 2 is a perspective view of the delivery device, parts being broken away.

Fig. 2a illustrates the forward end of the feeding chute.

Fig. 3 is a view looking into the rotary hollow drum body provided with an inner cone forming part of the delivery device and a view of the parts surrounding the hollow drum body.

Fig. 4 is a longitudinal section of said hollow drum body with the magazine connected thereto.

Fig. 5 is a side view of the end of the magazine, and

Fig. 6 is a plan view of the pivoting removing tool in the neighbourhood of the lead sealing tool.

In the drawings 1 indicates the driving shaft which is driven by means of a motor 2 and is supported on the housing 3 of the automatic sealing machine, and on which shaft there is arranged a driving pulley, not shown. The upper pulley is indicated at 4 and an endless belt passed over these pulleys is indicated at 5. An intermediate pulley driven by this belt is shown at 6 and the endless belt is provided at regular intervals with pairs of wire grips 7, each forming two adjacent triangular projections. Each pair of said grips forms a lifter for seal caps or slotted blanks 51 arranged haphazard in a lower storage container 8, the endless belt 5 being passed through this storage container. The lifters or grips 7 on the belt 5 convey the seal caps separately or continuously over the inclined plane 9 into the box 10 with an inclined base 11. A connecting passage or funnel 12 leads from the box 10 into the inner cone of a hollow drum body 13 over which is belt 5. The hollow body whose outer wall is cylindrical, is provided on the outside with grooves 44 and is supported on guide rollers 45, 46 which engage partly within said grooves and thus prevent axial movement 55

of said hollow body. The hollow body is pressed on to said guide rollers by belt 5. The seal caps are introduced into the cone which is open on both sides and widens towards the front through the narrow opening thereof.

In order to prevent a too quick passage of the seal cases through the cone, an arm 14 fixed to the machine frame 3 is arranged to project into said cone and has an axle 15 on which is supported a flap 16 provided with perforations 16' and which swings freely thereon. Within drum 13 there is provided a longitudinal groove 18, whereas a spring 19 projects beyond the periphery of said drum 13 at the front.

Below drum 13, at the free end thereof, there is arranged a rubber roller 20 driven from intermediate shaft 6 and which rotates in the same direction as the drum 13 (indicated by arrow, Fig. 3). Above the rubber roller 20 there branch off tracks for the seal cases. The roller 20 serves to keep the seal blank riding on it to rotate until the slot in the latter is aligned with the end of the riding rail 24; if such an alignment does not take place during one revolution of the cone 13, the said spring 19 lifts the blank into the chute 22. The track or chute 22 on the left of roller 20 (Figs. 2 and 3) leads back to storage container 8, whilst the other track or chute 23 on the right serves as a magazine for the seal caps passing to the sealing point. This magazine 23 is twisted so that the seal cases remain upright at the top while at the lower end of the magazine they leave the magazine with the base upwards.

In the magazine 23 there is provided a riding rail 24 preferably extending along one wall of said chute 23 on which the seal caps 51 pass from top to bottom astride said rail by means of slots provided in said caps. The end of the magazine 40 is, as shown in Fig. 5, provided with a spring 25 which prevents a premature ejection of the cases.

Below the point of discharge of said magazine 23 there is pivoted at 27 on the machine frame feeding member 26 in the form of a lever swingable about 21, which member serves to receive said seal cases. Said lever 26 has in its rear part a guide slot 28 in which engages a pin 29 which is fixed to a horizontally arranged plate 30. This plate is moved by means of the rod 31 from an eccentric on the driving shaft 1 (not shown). The lever 26 carries at its forward end a plate 26' as well as an extension 32 curved radially about the middle point of the axle 21 and on the centre longitudinal portion of which a riding rail 33 is similarly radially curved. The latter corre-

sponds in height to the depth of the slot in the seal caps. Moreover, rail 33 has at the front end thereof a thickened or enlarged part 33' which decreases gradually towards the rear but which increases sharply from the front.

On an extension 34 of the lever 26 adjacent the slot 28 there is fixed a spring 35 which has at its front part an extension 36 bent over in a right angle. The plate 30 also serves to move backwards and forwards a slide 37 with which seal discs (not shown) held in stacked relation in tube 38 are conveyed one by one from said magazine tube 38 into the matrix 39.

The sealing tool is indicated at 40 while 41 indicates the stamp through which the seal cap and a cardboard disc from magazine 38 are brought together with the string of a package 50 inserted in the slot 42 of the matrix 39.

A protecting plate 43 protects the front part of the lever 26 as well as the seal cap to be transported therewith.

The method of operation of the automatic machine is as follows:

The seal caps in the storage container 8 are, by means of lifters 7 fixed on the endless belt 5, conveyed into the box 10 and from there through the connecting passage or funnel 12 into the rearward end of the inner cone of drum 13. At each passage of a seal cap the flap 16 is raised slightly by the said cap and then swings back.

The seal cap which arrives in the forward part of the cone 13 may now be lying either on its back or on the edge thereof. If it lies on the edge it passes during rotation of the cone into the lower left quadrant thereof (Fig. 2) with a part of its edge in the longitudinal slot 18 and in the course of rotation of the cone it is caused to tip up so that it comes to rest on its back. When the cap falls out of the cone it again tips up and lies with the open side towards the front and with the side wall on the rubber roller 20. In this position it is held by the upper end of the riding rail 24 until the two oppositely disposed slots of the cap lie parallel to rail 24. The seal cap is therefore set in rotation by the rubber roller 20. As soon as said slots are in alignment with rail 24 the cap drops down into the magazine 23.

If a cap, instead of lying on its back, lies on edge and leaves the cone tipping over, it comes to rest on the rubber roller with its back towards the front, and from this position it is thrown out by abutting against spring 19 into track 22 and back into the storage container 8.

This rejection of a seal cap may also occur if the same lies correctly on the rubber roller but the rotation of the cap with respect to rail 24 has not ended so that the cap is still engaged by the spring 19.

The cap issuing from the magazine 23 falls with the edges on the plate 26' of the lever 26 and with the slot on the rail 33 thereof. Spring 35 with extension 36 rests against the spring 25 and assumes the position I. The other caps in the magazine 23 fall down under the action of their own weight. As soon as the lever 26 with the plate 26' is swung towards the tool 40 arranged over the matrix 39, the spring 25 is raised on account of the thickened part 33' which projects above the slot of the cap and which thus provides an abutment to the cap lying on the plate 26', and this cap now comes completely out of range of the magazine 23. At this moment while lever 26 is being moved toward tool 40 the extension 36 of the spring 35 moves underneath the spring

25 from the position I over the back of the cap into position II so that during further movement to sealing tool 40 the said case or cap cannot fall out from the plate 26'.

5 The next cap falling from out the magazine 23 then comes to lie on the end of the riding rail 33 behind the thickened part 33' but always remains lying directly under the outlet opening of the magazine where it is held fast by the spring 25 whilst the flat part 32 of lever 26 and the end of the rail 33 move from under this seal cap.

10 During the feeding movement of the lever 26 from the left to the right two blanks are situated upon the lever immediately upon leaving the position of Fig. 5, one of which issues from the magazine 23 at the beginning of the movement. This latter blank, therefore, first comes to sit immediately back of the front blank and gradually becomes more and more separated thereof upon the further movement of the lever 26. The front blank is fed into the sealing tool, while the rear blank blocks the magazine 23. The lever 26, therefore, is moved from underneath the rear blank. Upon the return movement of the lever 26, i. e. when the parts 29, 30, 31, 37 and 38 (Fig. 6) are moved backward and the lever 26 is swung from the right to the left, the plate 26' is empty and only the said rear blank is upon the lever 26. During this latter movement the tip of the rail 24 forms a stop for the said rear blank which blocks the magazine 23, when the lever 26 is moved from underneath the blank. Towards the end of the return movement, viz. when the swelling 33' comes to lie underneath this latter blank, the latter is tipped somewhat until it finally again occupies the position shown in Fig. 5.

15 The location of the cap lying on the plate 26' in the sealing tool 40 is known in the art. It may also be mentioned that extension 36 of the spring 35 connected therewith does not pass therewith into the tool 40, a part of the latter however serving as a stop for the spring extension 36 while the spring 35 passes into position III which, however, it again leaves in the backward movement of the lever 26 in order to return into its normal position II.

20 Towards the end of the backward movement of the lever 26 the cap located on the end of the rail 33 moves over the thickened part 33' and finally passes into the position in front of said thickened part as shown in Fig. 5. Accordingly, the spring 35 again comes into position I on account of the spring 25 acting as a stop for the part 36.

25 The device functions in such a manner that simultaneously during the movement of the case from the magazine 23 into the sealing tool 40 a disc from the magazine 38 is conveyed by means of the slide 37 into the matrix 39.

30 I claim:

35 A feeding mechanism for delivering slotted blanks to seal-stamping machines of the character described, comprising in combination a delivery device, a pickup-and-kickout device, and a feeding device proper; the said first device comprising a rotary drum of internally conical section which widens towards the delivery end, means projecting into the latter for retarding the delivery of the said blanks, a longitudinal groove on the inside of said drum for the purpose of positioning the said blanks, and a spring finger secured to the rim of the delivery end of the said drum cooperating with the said second device;

the second device comprising a forked chute, a roller rotating at the top of said chute and below the said delivery end onto which the said blanks are delivered one by one for the purpose of positioning them with respect to the slots thereof, a riding rail for the aligned blanks in the one fork of said chute, and the other fork of the said chute forming the kickout channel for the non-aligned blanks which are lifted thereinto by the said spring finger; and the third device comprising at the lower end of the pickup channel a

5 curved and slotted pivoting arm, a curved riding rail secured to one end of the said arm and being provided with a swelling at its forward end, a spring secured to the said arm having its free end bent over at right angles so as to lie immediately on top of the said arm, and a second spring secured to the end of the said pickup channel to counteract the said first spring for the purpose described.
